SLICING MACHINE

Charles T. Walter, Chicago, Ill., assignor, by
mesne assignments, to Industrial Patents Cor-
poration, Chicago, Ill., a corporation of Dela-
ware

Application June 29, 1931, Serial No. 547,495

9 Claims. (Cl. 146—113)

The invention relates to a slicing machine and more particularly to the means associated with the carriage or article feed whereby provision is had for automatically or manually throwing the feed drive out of gear to prevent injury to the machine or parts thereof.

The invention provides a slicing machine feed mechanism which is at all times under control to be thrown into or out of action as required without affecting the slicing or cutting mechanism and which assures the automatic stopping of the carriage when approaching the limit of its forward feeding movement, thereby obviating damage to the cutter or other part of the machine.

The invention is designed for general use in slicing machines, hence, in adapting the same for a particular make or type of machine, it will be readily understood that changes may be resorted to within the scope of the appended claims without departing from the nature of the invention.

For a full understanding of the invention and the merits thereof, reference is to be had to the drawings hereto attached and the subjoined description, in which corresponding parts are designated in the several views of the drawings and referred to in the specification by like reference characters.

30 In the drawings:—

Figure 1 is a side elevation of a carriage and associated parts illustrative of an embodiment of the invention.

Fig. 2 is an end view of the parts shown in Fig. 1.

Fig. 3 is a view similar to Fig. 2 as seen from the opposite end.

Fig. 4 is a detail view of the pivoted stop and attached arm for automatically throwing the carriage out of gear to arrest its advance.

The numeral 1 designates the body of the carriage formed with opposed aligned sleeves 2 through which passes a longitudinally extending feed screw 3. A bracket 4 forms in effect a part of the carriage and receives a holder 5 for receiving the article to be sliced. The numeral 6 designates a table or other fixed part of the machine frame disposed beneath the holder 5 and to which is attached a notched plate or strip 7. A shaft 8 is mounted in webs of the bracket 4 and receives a transversely positionable nut section 9 which is secured thereto to move therewith. A handle 10 is fast to the nut section 9 and provides convenient means for manipulation thereof.

55 The nut section is disposed between the sleeves

2 and is formed with threaded segments to match and coat with the screw threads of the feed screw 3 to advance the carriage in a longitudinal direction when the machine is in active operation. A coiled spring 11 is mounted on an end portion 30 of the shaft 8 and is secured thereto at one end, its opposite end being engaged with the carriage in any manner.

This spring 11 is torsionally tensioned to normally hold the feed nut section 9 transversely 65 positioned away from and out of engagement with the longitudinally extending feed screw. As has just been indicated the spring 11 provides means that continuously presses the nut section in a direction from the position whereat the nut section engages the feed screw. The spring 11 however provides means which is yieldable so as to permit the nut section to be forcibly moved against the constant pressure of the spring to and into the position whereat the nut section 75 engages the feed screw. Consequently the spring 11 may be considered as broadly providing yieldable pressing means by which the nut section is constantly pressed in a transverse direction leading from the screw engaging or operating position for the nut member towards the normal or inoperative position for the nut member, to wit towards that position in which it is impossible for the nut section to be engaged by the feed screw as the latter rotates. A stop 12 which is 80 slidably mounted in one of the bracket webs and which is movable in the direction of the movement of the carriage projects across the path of the nut section 9 and holds it in engagement with the feed screw against the tension of the spring 85 11. The stop 12 is sometimes referred to as the holding stop and it may be referred to as a locking stop on a member movably mounted on and relative to the carriage body 1. The member which comprises the holding stop 12 as a part 90 95 thereof comprises not only the member 12 but also the parts 13 and 14 hereinafter referred to.

An arm 13 receives the stop 12 and is connected to an operating rod 14 slidably mounted in the bracket webs and also movable in the direction of the movement of the carriage. An expandable helical spring 15 is mounted on the rod 14 and normally urges it in one direction with the stop 12 projected in the path of the nut section 9. A lever 16 coacts with an element 17 connected with the arm 13 to admit of sliding the bar 14 to throw the stop 12 out of the path of the nut section 9 to stop the feed of the carriage at will.

A stop or abutment 18 is mounted so as to per- 110

mit a limited angular movement necessary for the full functioning of the particular stop or abutment 18 and of an arm 19 thereupon is disposed in the path of the bar 14 to be engaged thereby and automatically throw the carriage out of gear by effecting a withdrawal of the stop 12 out of the path of the feed nut section 9. The arm 19 projects from the stop 18 and is disposed in the path of a finger 20 or like part projecting from the feed nut section 9 to positively actuate the same in the event of the spring 11 failing to function from any cause, thereby guarding against damage which would result from an overfeed of the carriage. The stop 18 is mounted upon a fixed part of the machine and not upon the carriage.

The stop 18 is pivoted and the arm 19 which is connected with the pivot of the stop 18 is adapted to be actuated to swing the finger 20 outwardly should the spring 11 fail to disengage the nut section from the feed screw. The engagement of the arm 19 with the finger 20 will hold the stop 18 until the slidable operating member 14 moves the slidable stop 12 out of engaging with the nut section and if the said spring 11 fails to function the continued movement of the carriage will actuate the pivoted stop and swing the arm 19 and the finger outwardly and thereby disengage the nut section from the feed screw.

30 A lever 21 is mounted upon the carriage 1 and is formed with a segment extension 22 to engage a notch of the notched plate or strip 7 and hold the carriage stationary when it is desired to use the ordinary hand-operated drop-knife to cut off an end of a loin of pork or for any other cause. This extension 22 is notched or slotted, as indicated at 23 to receive a pin or projection 24 at the side of an arm 25 secured to an end of the shaft 8. When the lever 21 is thrown into engagement with the part 7, the shaft 8 is rocked to throw the feed nut section 9 clear of the feed screw. This arrangement also admits of throwing the lever 21 out of engagement with the part 7 when the lever 10 is operated to throw the nut section 9 into engagement with the feed screw. The lever 21 functions as a lock member in conjunction with a fixed part of the machine to hold the carriage stationary. The pin and slot connection 24-23 results in a co-ordinate movement of the parts 21 and 10 while admitting of a limited movement to throw the nut section 9 into and out of engagement with the feed screw. By this construction, when the lever 21 is operated to move its portion 22 in engagement with the notched plate, the arm 25 of the shaft 8 will be oscillated and will simultaneously move the nut section out of engagement with the feed screw, and when the nut section is moved into engagement with the feed screw the arm 25 will be oscillated to carry the portion 22 of the lever 21 out of engagement with the notched plate 7.

What is claimed is:

1. The combination with the carriage of a slicing machine and a cooperating feed screw of a nut section on the carriage normally held out of engagement with the feed screw, a stop for holding the nut section in engagement with the feed screw, said stop being slidably mounted on the carriage and movable in the direction of the movement of the carriage, a slidable spring actuated member associated with said stop and also movable in the direction of the movement of the carriage, a stop in the path of the spring actuated member for automatic actuation thereof to move the nut section engaging stop out of

engagement, and manually operable means for sliding the said spring actuated member at will to arrest the movement of the carriage.

2. The combination with the carriage of a slicing machine and a cooperating feed screw of a nut section on the carriage normally held out of engagement with the feed screw, a stop for holding the nut section in engagement with the feed screw, said stop being slidably mounted on the carriage and movable in the direction of the movement of the carriage, a slidable member mounted on the carriage and also movable in the direction of the movement of the same for actuating the slidable stop, a stop in the path of the slidable member, and a lever on the carriage for operating the slide member at will to effect a stopping of the carriage.

3. The combination with the carriage of a slicing machine and a cooperating feed screw of a nut section on the carriage normally held out of engagement with the feed screw, a stop for holding the nut section in engagement with the feed screw an operating member connected with the stop, a pivoted stop located in the path of the operating member for effecting release of the nut section, and an arm projecting from the pivoted stop and engageable with a part of the nut section to hold the pivoted stop for effecting a movement of the operating member to release the nut section, said arm being also adapted to positively assure disengagement thereof from the feed nut.

4. The combination with the carriage of a slicing machine and a cooperating feed screw, of a nut section on the carriage, a shaft connected with the nut section and having an arm, a lock member movably mounted on the carriage engageable with the fixed part of the machine to hold the carriage stationary, and connecting means between the lock member and the arm of the shaft to cause simultaneous movement of the nut section and the lock member to disengage the nut section from the feed shaft when the lock member is moved into engagement with the said fixed part and to disengage the lock member therefrom when the nut section is moved into engagement with the feed screw.

5. The combination with the carriage of a slicing machine and a cooperating feed screw, of a nut section on the carriage, a movable lock member mounted on the carriage and adapted to engage a fixed portion of the machine, means for connecting the lock member with the nut section for disengaging the latter from the feed screw when the lock member is moved into engagement with the said fixed part and to disengage the lock member therefrom when the nut section is moved into engagement with the feed screw, a stop to hold the nut section in engagement with the feed screw, a slide associated with the said stop, a manually operable member for actuating the slide at will, a pivoted stop in the path of said slide, and an arm projected from the pivoted stop and adapted to engage a part of the nut section to hold the pivoted stop while the slide is being actuated and to effect a positive movement of the nut section after the same has been released.

6. In combination with a movable carriage of a slicing machine and a cooperating longitudinally extending feed screw for the carriage, of a transversely positionable nut section on the carriage normally yieldably held in inoperative position away from engagement with the feed screw by yieldable pressing means associated with

- the nut section, a longitudinally extending holding stop arranged to overlap said nut section upon the latter being forced against the pressing effect of the yieldable pressing means into operative position with respect to the feed screw and which holding stop is arranged to lock the nut section in operative engagement with the feed screw until the holding stop is forcibly moved from said locking position, said holding stop being slidably mounted on the carriage and longitudinally movable in respect to the carriage and means providing a stop or abutment that is capable of limited movement and which abutment is arranged for causing movement of the holding stop in a direction to release or unlock the nut section and thereby permit movement of the nut section from engagement with the feed screw upon the carriage moving the member that carries or provides said slidably mounted locking stop into engagement with said abutment, which last mentioned means that provides said abutment is also provided with mechanism associated with said abutment and constructed so that should the yielding pressing means fail to effect full movement of the nut section to inoperative position in respect to the feed screw following a release or unlocking of the nut section by the locking stop whereby the carriage over-travels or tends to do so—there will be effected a positive and automatic moving of the nut section away from the feed screw to inoperative position.
7. The combination, with a longitudinally movable carriage of a slicing machine and a cooperating longitudinally extending feed screw along which the carriage moves, of a nut section on the carriage normally held out of engagement with the feed screw, a stop carried by the carriage and movable with respect to the carriage and arranged for holding the nut section in engagement with the feed screw, means positioned for engagement by a member connected with the stop for effecting a movement of the stop from full nut holding position upon movement of the carriage to a particular position in respect to said means and for causing a release of the nut section when a sufficient movement of the carriage relative to the stop has been effected whereby the nut section is free to move from said feed screw engaging position, means comprising a spring associated with said nut section for throwing the nut section out of engagement with the feed screw upon the release of the nut section by said stop, and means for positively and automatically moving said nut section out of engagement with the feed screw should said spring means fail to operate and should said carriage consequently tend to continue to travel because of such failure of the spring means to operate.
8. The combination with the carriage of a slicing machine and a cooperating feed screw, of a nut section on the carriage movable into and out of engagement with the feed screw, a member on the carriage engageable with a fixed part of the machine to hold the carriage stationary, and means connecting said member with the nut section for causing simultaneous movement of said member and the nut section to disengage the nut section from the feed screw when said member is moved into engagement with the fixed part of the machine and to disengage said member from said fixed part when the nut section is moved into engagement with the feed screw.
9. The combination with a carriage of a slicing machine and a cooperating feed screw of a nut section on the carriage, a shaft connected to and movable with the nut section, a locking member on the carriage adapted to engage with a fixed part of the machine and hold the carriage stationary and cooperating means between said lock member and the shaft to effect simultaneous movement of the lock member and the nut section to disengage the nut section from the feed screw when the lock section engages said fixed part and to disengage the lock section when the nut is moved into engagement with the feed screw.
